UNITED STATES PATENT OFFICE.

HENRY KIELBERG, OF MARTINS FERRY, OHIO, ASSIGNOR TO WHEELING STEEL CORPORATION, OF WHEELING, WEST VIRGINIA, A CORPORATION OF DELAWARE.

STOVEPIPE STRUCTURE.

Application filed September 29, 1928. Serial No. 309,305.

This invention relates broadly to stovepipe structures, and more specifically to attaching means for the meeting edges of stovepipe sections.

5 The primary object of the invention is to provide a stovepipe section having its meeting edges shaped for interengagement and provided with means whereby, when interengaged, said edges are effectually secured 10 against chance disengagement.

A further object is to provide a stovepipe section of the character mentioned wherein the meeting edges carry lugs adapted to cooperate for securing said edges in place and 15 wherein the operations of interengaging and disengaging said lugs are readily effected by hand.

A still further object is to provide, in a structure of the character mentioned, lugs 20 having forms which assure their assuming positive interengagement when disposed in their operative positions.

In describing the invention in detail, reference is herein had to the accompanying 25 drawings, in which—

Figure 1 is a perspective view of a section of stovepipe embodying the invention, the edges being shown in unattached relation;

Figure 2 is a similar view showing the section twisted into position for introducing the lugs of one edge past those of the other, as 30 in the attaching operation;

Figure 3 is a view similar to Fig. 1, showing the edges occupying attached relation;

Figure 4 is an enlarged detail view of a fragmentary portion of the stovepipe section; and—

Figures 5 and 6 are enlarged sections on lines 5—5 and 6—6, respectively, of Fig. 3.

40 Referring to said drawings, 1 designates the body of a section of stovepipe formed of light-gauge sheet metal, in which one of the longitudinal edge portions is first turned outward and back upon itself to form a

45 member 2 of narrow width which closely overlies the adjacent portion of the metal body 1, and is thence returned parallel to and at a spaced distance from said member 2, forming a second member 3. Thus, there 50 is provided between the members 2 and 3 an open longitudinally extending channel or pocket 4 adapted for the reception of the opposite longitudinal edge portion.

The member 3 has formed thereon

throughout its length a plurality of short 55 tongue-like projections which are turned back to lie more or less closely against its inner surface, forming lugs 5, said lugs occupying spaced relation.

The opposite longitudinal edge of the pipe 60 body 1 has formed thereon a plurality of tongue-like projections which are turned back to lie against the outer surface of said body, forming lugs 6. Said lugs 6, spaced relatively to correspond with the spacing of 65 the lugs 5, are disposed directly opposite the last mentioned lugs.

Each of the lugs 6 has formed therein a series of corrugations of a height substantially equal to the width of the channel or 70 pocket 4, as shown at 7, and thus presents to the opposite lug 5 such a substantial thickness of abutment, as is best shown in Figs. 5 and 6, that positive interengagement between cooperating lugs is assured. 75

To effect joining of the edges of the stovepipe section, said section is sprung or twisted to position the lugs 6 laterally with respect to the lugs 5, as shown in Fig. 2, whereupon said lugs 6 may be introduced in the 80 pocket 4 without hindrance from the lugs 5, following which the edges are relatively shifted longitudinally to dispose the lugs in edge-to-edge abutting relation.

I am aware that prior stovepipe structures 85 of similar formation have embodied hooks which interengage one with the other for securing the meeting edges in attached relation. It will be noted, however, that in the present invention the lugs 5 and 6 have 90 their edges disposed in relatively seated relation and that each lug 6, having the corrugated formation disclosed, provides an abutment of such substantial thickness, as compared with the corresponding dimension 95 of the pocket 4, that positive interengagement is had with the terminal edge of the adjacent lug 5.

What is claimed is—

1. In a stovepipe section of the character 100 described, having one of its edge portions bent to form an open longitudinally extending pocket for the reception of the opposite edge, tongue-like lugs formed on the outer pocket-forming member and occupying underlying relation to the latter, and corrugated tongue-like lugs formed on and occupying overlying seated relation to the op-

posite edge, the lugs of one edge being adapted to abut the lugs of the other edge for securing said edges in attached relation.

2. In a stovepipe section having one of its edge portions shaped to form a longitudinal pocket, rearwardly turned lugs formed on said edge portion and located internally of said pocket, and rearwardly directed lugs formed on and occupying seated relation to the exterior surface of the opposite edge portion of said section, the last mentioned lugs being provided with corrugations of a height substantially corresponding to the width of said pocket, the lugs of one edge being

adapted to abut those of the other for securing said edges in attached relation. 15

3. In a stovepipe section having edges of slip-joint type, one of said edges having therein a pocket for the reception of the other edge, rearwardly directed lugs carried by one edge interiorly of said pocket, and rearwardly directed lugs carried by the other edge and adapted to be received in said pocket in abutting relation to the first mentioned lugs, the lugs of one of said edges 20 25 being corrugated.

In testimony whereof, I affix my signature.

HENRY KIELBERG.
